UNITED STATES PATENT OFFICE

2,235,799

SIDE FRAME

Robert B. Cottrell, Chicago, Ill., assignor to American Steel Foundries, Chicago, Ill., a corporation of New Jersey

Application April 10, 1939, Serial No. 267,126

4 Claims. (Cl. 105—206)

My invention relates to a side frame for a railway freight car truck and specifically to such a side frame of the form commonly called truss type. Such a construction involves a compression member, a tension member and one or more struts or columns joining the members, said members usually being so formed as to merge at their ends in a structure associated with some form of journal connecting means.

An object of my invention is to devise an improved form of the type of side frame shown in my co-pending applications Serial Nos. 196,035 and 196,036, both filed in the United States Patent Office on March 15, 1938, and the latter of which has matured as U. S. Letters Patent No. 2,188,641, granted January 30, 1940. My said novel form of side frame as previously described is devised to afford a particularly high rail clearance while at the same time meeting the present standard test requirements in an eminently satisfactory manner. As shown herein and in said co-pending applications, my said novel form of side frame is designed for association with a connecting bolster and one or more bolster insert castings designed to facilitate connection of the bolster end with the side frame and the associated spring group. The forms of said insert castings are shown in detail in the aforesaid co-pending applications.

Another object of my invention is to devise such a form of side frame as that above described wherein the web of the tension member will be at the top side of said member and will be formed substantially as a continuation of the top chord of the spring seat portion thereof, the flanges of said tension member extending downwardly and being connected by spaced struts as hereafter described in detail.

My novel structure as herein described contemplates the above-mentioned novel arrangement in combination with the novel column structure described in my said co-pending application Serial No. 196,035 together with other features disclosed and described in the associated drawings and the description thereof together with the appended claims.

Figure 1 is a side elevation of my novel side frame structure, only one-half of the frame being shown inasmuch as opposite ends of the frame are similar in form.

Figure 2 is a bottom plan view of the side frame structure shown in Figure 1, and Figure 3 is a top plan view thereof.

Figure 4 is a sectional view in a plane bisecting the structure shown in Figures 1, 2 and 3 taken

substantially in the transverse vertical plan indicated by the line 4—4 of Figure 1.

Figure 5 is a fragmentary view taken in horizontal plane indicated by the line 5—5 of Figure 1.

Figure 6 is a sectional view taken in the vertical plane substantially as indicated by the line 6—6 of Figure 1, the section being taken through the juncture of the column with the tension member.

Figure 7 is a section view through the diagonal portion of the tension member taken substantially as indicated by the line 7—7 of Figure 1.

Describing the structure in greater detail, the side frame comprises the compression member 2 and the tension member 4 merging adjacent their ends as at 6 with the integrally formed journal box structure 8. Columns 10, 10 are integrally formed with the compression and tension member and define therewith the bolster opening 12, said bolster opening having uniform width at the top and bottom as indicated at 14, 14 and the somewhat restricted width therebetween due to the formation thereon of the centrally located guide surface 16 with the vertical flange 18, said surface having concave cylindrical form as best seen in the top plan view of Figure 3, said view also showing the tapered character of the vertical guide flange 18 notched at the top as indicated at 20 for a purpose more fully explained in my said co-pending application Serial No. 196,035.

The compression member 2 is formed with the web 22 at its top side and downwardly projecting lateral flanges, said lateral flanges being joined by the integrally formed spaced ties indicated at 24 and 26 over the window opening 27 and having at the transverse center line of the frame the tie member 29 (Figure 4) which merges with the reflanged edges of said lateral flanges along the portions of said flanges above the window opening 12 as best seen at 31, 31 (Figure 3). The tension member 4 is likewise inverted U-shape in cross section having the web 28 (Figure 7) and the side flanges 30 and 32 reflanged as indicated at 34, 34, said reflanged portions being beaded at their outer edges as indicated at 36, 36, said beads 45 extending from the juncture of the tension member with the journal box 8 throughout the length of the diagonal portion thereof and merging at their inner ends as at 38 (Figure 2). The flanges of the tension member are joined by the spaced ties indicated at 40 and 42, the tie 40 merging with the reflanged portions 34 along relatively large radii as indicated at 44, 44. The tie 42 likewise merges with said reflanged portions at its inner edge along the radii indicated at 46, 46 and 55.

its outer edge is prolonged as indicated at 48, 48 to merge with the edges of said reflanged portions 34, 34 over an extensive area.

5 The central horizontal portion of the tension member is of box section having the top web 50, the bottom web 52 and the central longitudinal flange 54 as well as side walls 56 and 58 of reduced height to form a shallow box section. The top chord 50 is widened to form a spring seat 60, 10 said spring seat being defined at its opposite edges by the upstanding flanges 62 and 64 beaded along their upper edges as indicated at 66 and 68. The juncture of the upstanding flanges with the horizontal spring seat is reinforced by the ribs 70, 70. 15 16 Adjacent the juncture of the upper end of the column 10 with the compression member 2 is formed the usual brake hanger bracket 72 on the inboard face of the side frame. The column is or general U shape in cross section as best seen 20 at 14 (Figure 5) and the web thereof is substantially vertical throughout its length, said web extending from the top of the window opening 12 to the top chord 50 of the spring seat and merging therewith. As previously indicated, the window opening defined by the columns has equal 25 width at the top and at the bottom with the centrally located concave cylindrical bolster guide surfaces 16 interrupted at the middle by the vertical guide flange 18. It may be noted 30 that the bolster guide surface 16 is widened laterally as compared with the remainder of the column, thus affording somewhat greater bearing surface for bolster engagement. Below the guide surface 16 the web of the column is cored out 35 as indicated at 76 (Figure 4), reducing the weight of the casting in an area which would otherwise have an excess of metal. At the upper end of the column there is cored out also the transverse slot 78 to facilitate the casting operation and 40 prevent the formation of cracks.

45 At its lower end the column is flared to a greater width as best seen at 80, 80 (Figure 4) to merge as at 82, 82 (Figure 5) with the inturned end portions of the upstanding flanges 62 and 64, the structure being continued in a smooth shallow curve devoid of any sharp turns or angles.

50 In Figures 4 and 5 is shown a convenient method of arrangement of spring positioning means to be accommodated upon the spring seat 60, said 55 positioning means comprising the spaced triangular studs 86, 86, the central dowel 88 as well as lateral positioning means 90, 90 and guide pads 92, 92 integrally formed with the upstanding flanges at the sides of the spring seat. These figures also show a convenient method of affording drainage for the spring seat pocket in the form of the drain holes 94, 94 at the ends of the pocket and drain holes 96, 96 at the sides thereof. 60 It will be understood that the arrangement of spring positioning means and likewise the drainage openings may be modified to suit the convenience of the spring group to be incorporated in the truck structure. As shown, the 65 positioning dowels will accommodate a great variety of standard spring groups and friction absorbing devices of well known form.

70 At the base of the column and adjacent the middle web thereof may be cored out the drainage openings 84, 84, said openings also facilitating the casting operation by reducing the amount of metal at the juncture of the column with the top chord of the spring seat portion. The character of the structure in this arrangement is best 75 shown by the vertical sectional view of Figure 6

taken just outwardly of the web of the column and extending through the before-mentioned drainage openings 84, 84. At this point it will be seen that the upstanding flanges 62 and 64 have been drawn inwardly to merge with the flaring bottom portions 80, 80 of the column and likewise the side walls 56 and 58 of the shallow box section have been drawn closer together to form a substantial continuation with the flaring portions 80, 80 of the column and the flanges 62 10 and 64.

15 It will thus be seen that I have formed a very compact and unified structure at the juncture of the column with the tension member affording maximum simplicity with great strength. 15 The shallow box section with the upstanding flanges form a section (Figure 4) of great strength which at the same time permits the formation of a side frame of relatively shallow depth, thus affording maximum rail clearance 20 and a large area for the spring group.

25 It is to be understood that I do not wish to be limited by the exact embodiment of the device shown which is merely by way of illustration and not limitation as various and other forms of the 25 device will, of course, be apparent to those skilled in the art without departing from the spirit of the invention or the scope of the claims.

I claim:

30 1. In a truss side frame for a railway car truck, a compression member of inverted U-section, a tension member of inverted U-section, integral columns joining said members and forming therewith spaced window openings and an intervening bolster opening, said tension member 35 having beneath said bolster opening a horizontal portion of box section with a top chord thereof widened and formed with upstanding flanges defining a spring seat portion, said top chord being continuous with the web of said U-section 40 tension member outwardly of said columns, said upstanding flanges converging adjacent their ends toward said columns and merging with said web at the bases of said columns, each of said columns having a U-section with the side walls 45 thereof flaring adjacent their lower ends to merge with said converging flanges, each of said columns having a vertical web extending from said compression member to said tension member and interrupted centrally thereof by a bolster guide 50 portion, said guide portion comprising an arcuate wall interrupted centrally thereof by a vertical guide flange, all of said guide portion being spaced from the top of said bolster opening to afford entrance of an associated bolster end there- 55 above.

55 2. In a truss side frame for a railway car truck, a compression member of inverted U-section, a tension member of inverted U-section, integral columns joining said members and forming 60 therewith spaced window openings and an intervening bolster opening, said tension member having beneath said bolster opening a horizontal portion of box section with the top chord thereof widened and formed with upstanding 65 flanges defining a spring seat portion, said top chord extending beneath said columns and into diagonal portions of said tension member to merge therewith between said columns and the end of said frame, said upstanding flanges con- 70 verging adjacent their ends toward said columns, each of said columns having a U-section with the side walls thereof flaring adjacent their lower ends to merge with said converging flanges, each of said columns having a vertical web extending 75

from said compression member to said tension member and interrupted centrally thereof by a bolster guide portion, said bolster guide portion comprising a concave wall interrupted centrally thereof by a vertical guide flange, all of said guide portion being spaced from the top of said bolster opening to afford entrance of an associated bolster end thereabove, said converging flanges merging with said transverse webs along the inboard and outboard edges of the bases of said columns.

5. In a truss side frame for a railway car truck, a compression member of inverted U-section, a tension member having a horizontal spring seat portion and diagonal end portions, said diagonal end portions having transverse webs and depending flanges with inwardly projecting ledges at their edges, integral columns joining said members and forming therewith spaced window openings and an intervening bolster opening, said horizontal spring seat portion comprising a box section with the top chord thereof widened and formed with upstanding flanges defining a spring seat portion, said top chord extending beneath said columns and into diagonal portions of said tension member to merge therewith between said columns and the end of said frame, said upstanding flanges converging adjacent their ends toward said columns, each of said columns having a U-section with the side walls thereof flaring adjacent their lower ends to merge with said converging flanges, each of said columns having a vertical web extending from said compression member to said tension member and interrupted centrally thereof by a bolster guide portion, said bolster guide portion comprising a concave wall interrupted centrally thereof by a vertical guide flange, all of said guide portion being spaced from the top of said

bolster opening to afford entrance of an associated bolster end thereabove, said converging flanges merging with said transverse webs along the inboard and outboard edges of the bases of said columns.

4. In a truss side frame for a railway car truck, a compression member of inverted U-section, a tension member having a horizontal spring seat portion and diagonal end portions, said diagonal end portions having transverse webs and depending flanges with inwardly projecting ledges at their edges, integral columns joining said members and forming therewith spaced window openings and an intervening bolster opening, said horizontal spring seat portion comprising a box section with the top chord thereof widened and formed with upstanding flanges defining a spring seat portion, said top chord extending beneath said columns and into diagonal portions of said tension member to merge therewith between said columns and the end of said frame, said upstanding flanges converging adjacent their ends toward said columns, each of said columns having a U-section with the side walls thereof flaring adjacent their lower ends to merge with said converging flanges, each of said columns having a vertical web extending from said compression member to said tension member and interrupted centrally thereof by a bolster guide portion, said bolster guide portion comprising a concave wall interrupted centrally thereof by a vertical guide flange, all of said guide portion being spaced from the top of said bolster opening to afford entrance of an associated bolster end thereabove, the converging portions of said upstanding flanges merging with said transverse webs along the bases of said columns inboard and outboard of said frame.
